UNITED STATES PATENT OFFICE.

JOHN C. MITCHELL, OF NEWPORT NEWS, VIRGINIA.

SEALING THE JOINTS OF SECTIONAL CONCRETE PIPE.

1,054,857.

Specification of Letters Patent.

Patented Mar. 4, 1913.

Application filed March 15, 1909. Serial No. 483,644.

To all whom it may concern:

Be it known that I, JOHN C. MITCHELL, a citizen of the United States, residing at Newport News, county of Warwick, and State of Virginia, have invented certain new and useful Improvements in Sealing the Joints of Sectional Concrete Pipe, of which the following is a full, clear, and exact description.

10 This invention relates to sectional concrete pipe, more particularly to the making of the joints between the pipe sections, and has for its object to provide means for sealing the sections together in an effective and 15 expeditious manner.

In the annexed drawings I have illustrated the invention in the form which I consider to exhibit the best mode of applying the invention in practice, with special reference 20 to concrete pipe of the type described in the prior patent of Coleman Meriwether, No. 894,517, dated July 28, 1908, but I desire it understood that the invention is not limited to use with that particular kind of pipe.

25 Referring now to the drawings, Figure 1 is a longitudinal section of a concrete pipe, showing the circular band employed for closing the inner groove of the pipe-joint. Fig. 2 is a cross section on line II—II of 30 Fig. 1, showing also the device employed for forcing plastic or semi-liquid concrete into the joint-groove. Fig. 3 is a development of a portion of groove-closing band.

The pipe sections 1, 2, 3, illustrated in the 35 drawings, are cylindrical and are provided with "bell and spigot" ends formed in such manner as to leave an undercut groove, as 4, on the inside of the pipe when the sections are assembled with the spigot end of one 40 fitting into the bell end of its neighbor. Embedded in the pipe sections are suitable meshed reinforcing fabrics 5, which extend out of the ends of the sections and overlap each other in the said grooves, as shown at 45 6, Fig. 1. These grooves are to be filled with concrete, which, embedding the overlapping reinforcements, serves to bind the pipe sections firmly together.

7 designates a strip of resilient metal, 50 preferably sheet steel, curved to a more or less circular form and in circumferential extent or length equal to or very slightly less than the inner circumference of the pipe in which it is to be used. This band 7 is provided with a plurality of apertures 8, preferably rectangular, and over each aperture

is a suitable closure, for example a plate 9 sliding in guides or gib 10. Fixed securely at one end of the band is a member 11, and hinged thereto is a stiff bar or plate 12, the 60 free end of which is adapted to engage an inclined cam member 13 fixed on the other end of the band.

14 designates a device in the nature of a force-pump, the cross section of which is the same, in shape, as the form of the apertures 8 (in the present case rectangular) the size of said pump device in cross section being such that when inserted into one of the apertures and turned out of the radial position, as shown in Fig. 2, the device will fit the aperture closely and thereby prevent the leakage or escape of the liquid or semi-liquid concrete with which the groove is filled. Working in the casing or body portion 15 of the device is a piston or plunger 16 the reciprocation of which fills the casing with material (by suction) through the open forward end of the casing or body portion and expels the same again.

The method of using the devices described above is as follows: A pair of pipe sections being assembled as in Fig. 1, the lower part of the groove is packed with concrete by means of a trowel or other suitable implement, to a point about half way up the sides of the pipe. The band 7 is now placed in position, with the apertures 8 over the un-filled part of the groove and the bar 12 is forced firmly down against the member 13, 90 the inclined face of which, coöperating with the bar or plate 12, causes the band to be expanded against and into close conformity with the inner surface of the pipe. The pump device 14 is then filled with concrete 95 which is liquid enough to flow and is inserted, in the manner shown in Fig. 1, into the aperture nearest to the concrete already in the groove at one side of the pipe. The piston is then pushed in, expelling the concrete. The size of the pump or filling device is preferably so proportioned as to hold just enough, or slightly more than enough, to fill the groove up to the aperture next 100 above. When the concrete is seen at the level of the next upper aperture the filling device is withdrawn and the gate closed, which can be effected, by the exercise of a little dexterity without the escape of material through the aperture in which the 110 filling device had been inserted. The operations described are repeated up to the top

- of the pipe, then on the other side of the pipe, and lastly the remaining space at the center. As soon as the concrete has set sufficiently the band is loosened and stripped off, leaving the inner surface of the joint smooth and flush with the surface of the pipe sections. If preferred the lower part need not be filled with concrete before arranging the groove-closure or band, but the latter may be placed in position at once and the groove then filled entirely by means of the pump-device in the manner already described. Both methods have been found to be expeditious and thoroughly effective.
- 15 The devices described herein may be modified in various ways as to their details of construction, but I consider such changes to be within the proper scope of the invention as defined by the appended claims.
- 20 What I claim is:
1. A resilient metal band for closing the inner circumferential groove at the joint of a sectional concrete pipe, in combination with means for expanding the band to close 25 the circumferential groove, said means located entirely on said band and operating to maintain the metal band over the circumferential groove, said band having a plurality of perforations, and means for forcing concrete through said perforations into the circumferential groove.
  2. A substantially circular resilient metal band adapted to close a circumferential

groove on the inside of a pipe and whose circumferential extent or length is substantially equal to the inner circumference of the pipe in which it is to be used, said resilient band having means wholly supported thereon and leaving the conduit substantially unobstructed for removably maintaining the same in position and having perforations therein in combination with means on the interior of said conduit for forcing concrete or grout through said band into the circumferential groove.

3. A limber band having disconnected ends and adapted to be placed over an interior groove formed between individual sections of a conduit, said band comprising means on one end coöperating with means on the other to expand said band uniformly throughout its circumference into conformity with said conduit and cause the same to engage the concrete pipe at all points adjacent said groove, said coöperating means being readily disengageable from each other and so located and of such dimensions as to provide a substantially unobstructed passage in said conduit.

In testimony whereof I affix my signature in the presence of two subscribing witnesses.

JOHN C. MITCHELL.
